[57] CLAIM

The ornamental design for a swivel forcep screw driver holder for dental implants, as shown and described.

DESCRIPTION

FIG. 1 is a perspective view of a swivel forcep screw driver holder for dental implants, showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof; and

FIG. 7 is a right side elevational view thereof.

Fig. 1.

Fig. 2.

Fig. 3.

Fig. 4.

Fig. 5.

Fig. 6.

Fig. 7.
